UNITED STATES PATENT OFFICE.

HARRY LYNCH, OF DES MOINES, IOWA.

ATTACHMENT FOR PIPE-THREADING MACHINES.

Application filed December 22, 1921. Serial No. 524,153.

To all whom it may concern:

Be it known that I, HARRY LYNCH, a citizen of the United States, and a resident of Des Moines, in the county of Polk and State 5 of Iowa, have invented a certain new and useful Attachment for Pipe Threading Machines, of which the following is a specification.

The object of my invention is to provide 10 an attachment of very simple and inexpensive construction adapted to be combined with a pipe threading machine and an ordinary ratchet wrench structure, whereby an inexpensive pipe threading device may 15 be equipped with a ratchet operating means of efficient structure at a very small expense.

With this and other objects in view, my invention consists in the construction, arrangement and combination of the various 20 parts of my device, whereby the objects contemplated are attained, as hereinafter more fully set forth, pointed out in my claims, and illustrated in the accompanying drawings, in which:

25 Figure 1 shows a perspective view of a pipe threading device equipped with an attachment and a ratchet wrench, the attachment and combination embodying my invention.

30 Figure 2 shows a front elevation of the device installed on a pipe; and

Figure 3 shows a detailed, sectional view through the ratchet structure.

Pipe threading devices are made in different forms. I have illustrated one ordinary form of such a device in my drawings, and have used the reference numeral 10 to indicate generally the tubular body thereof.

35 Mounted in the body 10 are set screws 11, for fastening the body to a pipe, when the pipe is inserted into the body. The interior of the body is screw-threaded and receives an externally screw-threaded tubular member 12, forming part of what is ordinarily 40 called the die head.

45 Fixed to the outer end of the screw-threaded tubular member 12 is the taper pin plate 13. Rotatably but non-slidably mounted on the body 10 is an annular plate 14, from which the tapered pins 15 project upwardly through corresponding holes in the plate 13 of the die head.

50 On the upper surface of the plate 13 are ribs or the like 16 in which are formed slots 17, which contain the die segments 18. Projecting from the plate 13 on opposite sides

thereof are the tubular members 19 adapted to receive the inner end of a handle, which may be a piece of pipe or otherwise.

In cutting a thread on the end of a pipe, 60 the die head is screwed to its outer limit of movement; the end of the pipe is inserted through the tubular body 10 until one end is adjacent to the die segments 18.

The handle inserted into the tubular member 19 is then operated for rotating the die head, which will thus be screwed into the body 10. As the ends of the die segments 18 reach the end of the pipe, the threads will be cut in the outer surface of the pipe, as 70 the plate 13 moves toward the body 10 by virtue of the movement of the screw-threaded tubular member 12 into said body.

The parts heretofore described are of ordinary construction and in themselves do not 75 form my present invention.

With a device of the kind mentioned, it is necessary to use handles of considerable length, and great difficulty is found in operating the device where it must be operated 80 in a small space.

It is obvious that considerable leverage is necessary to form the screw-threads on the pipe, and it is therefore desirable to have 85 the handle structure.

The pipe threading devices with ratchets embodied as part of the regular construction are now known, but they are very expensive as compared with the device above described.

90 It is my purpose to provide an attachment, whereby a simple ratchet wrench may be employed and the advantage of the ratchet structure secured without adding the large expense necessary to make a ratchet pipe threading device of the ordinary construction.

Furthermore, even with ratchet structures of the kind in ordinary use, it is commonly necessary to employ a long handle so that 100 even the ordinary ratchet structures face the difficulty of operating in a small space.

105 My improved attachment comprises a cylindrical rod or the like 20, which is designed to be inserted into one of the tubular members 19. The rod 20 and the walls of the member 19 are provided with holes, which will register with each other and receive a locking pin 21.

110 On the outer end of the cylindrical rod 20 is a right-angled extension 22, angular in outline, as shown in Figure 1. The pin 21

and the holes in the rod 20 and the member 19 are so arranged that when the device is installed, the extension 22 is arranged parallel with the main axis of the device and 5 projecting away from there beyond the pipe threading device, as illustrated in the drawings in Figure 1.

The extension 22 is designed to receive an ordinary ratchet wrench 23, having the ordinary handle; and the ratchet structure 24, illustrated for instance in Figure 3.

It will be seen that where my attachment is employed, the ratchet handle may be used and can be moved to any position of rotation 15 around the member 22.

In Figure 2, I have illustrated the pipe threading device equipped with my attachment arranged adjacent to a ceiling 24^a and a side wall 25.

20 It will be seen that the ratchet wrench handle may be adjusted from its full line position shown in Figure 2 to its various dotted line positions, as illustrated, so that even though a small space is allowed for the 25 movement of the handle, the pipe threading device may be operated for cutting threads and the advantage of leverage retained.

To be sure, the leverage is not as good in 30 some positions of the ratchet handles as in others, but it is always possible to have some substantial leverage action.

The peculiar structure of the member 20 and its extension 22 is such as to make it possible to use an inexpensive ratchet

wrench with the more inexpensive forms of 35 pipe threading devices in an efficient manner.

It will be seen that my invention consists in the attachment and the combination thereof with other parts. 40

I claim as my invention:

1. The combination of a pipe cutting device, having a rotatable die head provided with a lateral extending tubular member, an attachment therefore having a portion 45 non-rotatably mounted in said tubular member and an extension projecting away from and beyond the pipe threading device in a line substantially parallel with the axis of the pipe threading device, said extension 50 being angular in outline, and a ratchet wrench mounted on said extension.

2. In a device of the class described, the combination of a pipe threading device, having a rotatable die head provided with a lateral projecting member, an attachment having a portion fixed to said laterally extending member with its longitudinal axis coinciding with the longitudinal axis of said lateral extending member, said attachment 55 having a right-angled extension projecting away from and beyond said pipe threading device and being angular in cross section, and a ratchet wrench mounted on said last described extension. 60

Des Moines, Iowa, October 13, 1921.

HARRY LYNCH.
